(57) **CLAIM**

The ornamental design for a high pressure cleaning apparatus, as shown and described.

DESCRIPTION

FIG. 1 is a front, left, top perspective view of a high pressure cleaning apparatus, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top elevational view thereof;

FIG. 8 is a bottom elevational view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 2;

FIG. 13 is an enlarged view of detail 13 in FIG. 2;

FIG. 14 is an enlarged view of detail 14 in FIG. 5;

FIG. 15 is an enlarged view of detail 15 in FIG. 5;

FIG. 16 is an enlarged view of detail 16 in FIG. 5;

FIG. 17 is an enlarged view of detail 17 in FIG. 6;

FIG. 18 is an enlarged view of detail 18 in FIG. 7; and,

FIG. 19 is an enlarged view of detail 19 in FIG. 8.

The dashed broken lines in the figures illustrate portions of the high pressure cleaning apparatus that form no part of the claimed design.

The dash-dot-dash broken lines are for notating enlarged views and form no part of the claimed design.

1 Claim, 17 Drawing Sheets
